E. H. Serrano

D. W. Raymond,
Attorney.

Inventor:

plate 45 secured to the inner face of the tubular post. The upper end of the lever 43 is pivotally mounted as at 46 to that portion of the rod 36 extending through the upper end of the tubular post 10 and a weighted pedal or treadle mechanism is associated with the lower end of the lever 43.

A treadle bar 47 extends through oppositely disposed slotted openings 48 and 49 in the lower end of the tubular post 10 and is pivotally mounted intermediate its ends within said post upon the horizontal pin 50 carried by an upstanding bracket arm 51. The end of the treadle bar 47 extending through the slotted opening 48 carries a treadle plate 52 while the end of the treadle bar 47 extending through the slotted opening 49 is calibrated as at 53 and has weights 54 adjustably mounted thereon by means of screws 55. An arm 56 is carried by and perpendicularly projects from the treadle bar 47 within the tubular post 10 and at a point between the treadle bar pivot 50 and the slotted opening 48, the upper end of the arm 56 carrying a roller 57 engaged with the adjacent side of the lever 43; a leaf spring 58 having one end attached as at 59 to the arm 57 intermediate the ends thereof has the other end thereof engaged with the side of the lever 43 as at 60 opposite the roller engagement 57.

To cushion the descending movement of the weighted end of the treadle bar 47 when the treadle plate 52 is relieved of foot pressure, there is provided a dash-pot device comprising a fluid cylinder 61 closed at its lower end and open at its upper end and pivotally supported intermediate its ends as at 62 in a pair of upstanding lugs 63 rising from the base plate 11 at opposite sides of the opening 64 through which the cylinder 61 extends. A tubular piston 65 is reciprocably mounted within the cylinder 61 and carries at its upper end a pair of lugs 66 to straddle the treadle bar 47 with openings 67 in said lugs to accommodate the mounting of a pivot pin 68. A downwardly opening spring-pressed valve 69 is carried by the bottom wall of the piston 65 and said piston 65 has a pair of vertically spaced annular grooves 70 in the outer wall thereof with openings 71 extending through the bottom walls of said grooves to permit the return of fluid to the cylinder 61 that passes upwardly between the piston and cylinder during descending movements of the piston.

With the treadle bar in the position illustrated in Figure 1, it is understood that the operator of the racket stringing machine has his foot on the treadle plate 52 to hold the weighted end of the treadle bar elevated. The string clamp 40 is then engaged with the racket string 42 and when the treadle plate is relieved of foot pressure, the weighted end of the treadle bar lowers, being cushioned by the dash pot construction, while the arm 50 carried by said treadle bar with the roller 57 engaged with the lever 43 moves said lever on its pivotal link connection 44 with the tubular post 10 to cause the upper end of the lever 43 to move the slide rod 36 that carries the string clamp 40. The weights 54 are adjustably mounted upon the calibrated end 53 of the treadle bar 47 to impart the desired tension to the engaged racket string and after such tension has been placed on the string, the clamp 26 is engaged with the string within the racket loop 18 to hold the string section so tensioned during shifting movements of the plate 13 for the tensioning of a second or succeeding section

of the string. When the treadle plate 52 has foot pressure applied thereto, the weighted end of the lever is elevated and the spring 58 carried by the arm 56 causes a reverse pivotal movement of the lever 43 and a corresponding reverse sliding movement of the rod 36 so that the clamp 40 carried by said rod 36 will again be positioned for proper engagement with a string section to be tensioned. The anti-friction bearing balls 37 permit an easy sliding movement of the rod 36. The bracket arm 39 and string gripper 40 are adjustably mounted on the bar 20 so that the string gripper 40 can be placed the same distance from the racket frame loop 18 when the same is shifted with plate 13 for gripping the racket string 42 to assure an even tension being imparted to all sections of the racket string.

While there is herein shown and described the preferred embodiment of the invention, it is to be understood that minor changes may be made in the details of construction, such as will fall within the scope of the invention as claimed.

I claim:

1. In a racket stringing machine, wherein a racket supporting head is mounted upon the upper end of a tubular post, string tensioning means including a rod slidable transversely of the upper end of the post beneath the head, a string gripper on one end of said rod, a substantially vertically disposed lever pivoted between its upper and lower end in the tubular post to the side wall thereof with the upper end of the lever pivotally attached to said slide rod and a weighted treadle bar extending transversely of the lower end of the post below the lower end of said lever and operatively engaged with the lower end of said lever.

2. In a racket stringing machine, wherein a racket supporting head is mounted upon the upper end of a tubular post, string tensioning means including a rod slidable transversely of the upper end of the post beneath the head, a string gripper on one end of said rod, a substantially vertically disposed lever pivoted between its upper and lower ends in the tubular post to the side wall thereof with the upper end of the lever pivotally attached to said slide rod and a weighted treadle bar extending transversely of the lower end of the post below the lower end of said lever and operatively engaged with the lower end of said lever, a channel guide at the upper end of the post through which the rod is slidable and anti-friction bearings in said guide for said rod.

3. In a racket stringing machine, wherein a racket supporting head is mounted upon the upper end of a tubular post, string tensioning means including a rod slidable transversely of the upper end of the post beneath the head, a string gripper on one end of said rod, a substantially vertically disposed lever pivoted between its upper and lower ends in the tubular post to the side wall thereof with the upper end of the lever pivotally attached to said slide rod and a weighted treadle bar extending transversely of the lower end of the post below the lower end of said lever and operatively engaged with the lower end of said lever, the connection between the treadle bar and lever including an arm carried by the treadle bar and having a roller at its free end engaged with one side of said lever and a spring on the arm engaged with the other side of the lever.

4. In a racket stringing machine, wherein a racket supporting head is mounted upon the upper end of a tubular post, string tensioning means including a rod slidable transversely of the upper end of the post beneath the head, a string gripper

per on one end of said rod, a substantially vertically disposed lever pivoted between its upper and lower ends in the tubular post to the side wall thereof with the upper end of the lever pivotally attached to said slide rod and a weighted treadle bar extending transversely of the lower end of the post below the lower end of said lever and operatively engaged with the lower end of said lever and a dash-pot construction associated with the treadle bar for cushioning descending movements of the weighted end thereof.

5. In a racket stringing machine, wherein a racket supporting head is mounted upon the upper end of a tubular post, string tensioning means including a rod slidable transversely of the upper end of the post beneath the head, a string gripper on one end of said rod, a substantially vertically disposed lever pivoted between its upper and lower ends in the tubular post to the side wall thereof with the upper end of the lever pivotally attached to said slide rod and a weighted treadle bar extending transversely of the lower end of the post below the lower end of said lever and operatively engaged with the lower end of said lever,

10 a channel guide at the upper end of the post through which the rod is slidable and anti-friction bearings in said guide for said rod and a dash-pot construction associated with the treadle bar for cushioning descending movements of the weighted end thereof.

6. In a racket stringing machine, wherein a racket supporting head is mounted upon the upper end of a tubular post, string tensioning means including a rod slidable transversely of the upper end of the post beneath the head, a string gripper adjustably mounted on one end of said rod whereby said gripper may engage a string section the same distance from a racket being strung to impart even tension to all sections of the racket string, a substantially vertically disposed lever pivoted between its upper and lower ends in the tubular post to the side wall thereof with the upper end of the lever pivotally attached to said slide rod and a weighted treadle bar extending transversely of the lower end of the post below the lower end of said lever and operatively engaged with the lower end of said lever.
